Inventor:

Godfrey W. Papke.

UNITED STATES PATENT OFFICE.

GODFREY W. PAPKE, OF ECHO, MINNESOTA.

THRESHING-MACHINE.

SPECIFICATION forming part of Letters Patent No. 573,479, dated December 22, 1896.

Application filed December 16, 1895. Serial No. 572,246. (No model.)

To all whom it may concern:

Be it known that I, GODFREY W. PAPKE, a citizen of the United States, residing at Echo, in the State of Minnesota, have invented certain new and useful Improvements in Threshing-Machines; and I do hereby declare the following to be a full, clear, and exact description of the invention, such as will enable others skilled in the art to which it appertains to make and use the same.

My invention relates to threshing-machines of the class in connection with which pneumatic stackers are employed, and has for its object to simplify the construction and improve the operation of the same.

To these ends my invention comprises the novel devices and combinations of devices hereinafter described, and defined in the claims.

The accompanying drawings illustrate the preferred form of my invention, wherein, like letters referring to like parts throughout the several views—

Figure 1 is a view in side elevation, showing a threshing-machine constructed in accordance with my invention, some parts being broken away and others being removed. Fig. 2 is a plan section taken on the irregular line $x' x'$ of Fig. 1. Fig. 3 is a front elevation of the parts shown in Fig. 1, and Fig. 4 is a vertical longitudinal section taken through the rear or delivery end of the thresher on the line $x^2 x^2$ of Fig. 2.

a indicates the thresher-frame and casing, a' the feed-deck, a^2 the cylinder, a^3 the cylinder-shaft, a^4 the vibrating separating-tables or rattle-rakes, a^5 the shoe provided with the separating sieves or riddles a^6 , a^7 the grain-delivery or shoe spout, and $a^8 a^9 a^{10}$ the folding or sectional pneumatic stacker-trunk or delivery-spout, all substantially of the ordinary construction. Certain other parts of the thresher have been omitted from the drawings, the same being well known and not being essential to a clear understanding of my invention.

In carrying out my invention the cylinder-shaft a^3 is extended at each end somewhat more than is ordinary and is mounted near its outer ends in bearings a^{11} , secured to the sides of the thresher-frame a . On its extreme ends the shaft a^3 is provided with pul-

leys $a^{12} a^{13}$, to one of which power is applied in the usual way. On the extended ends of this shaft a^3 , one at each end of the cylinder 55 a^2 , I secure a pair of fans b . These fans b are incased by fan-cases b' , secured to the frame a and open at their outer sides for the admission of air, as shown at b^2 .

b^3 are air-chutes leading one from each of the fan-cases b' and opening at the opposite sides of the flaring base of the lower section a^8 of the stacker trunk or tube $a^8 a^9$. Each of these chutes b^3 is provided with cut-off valves b^4 , which are controlled and set wherever desired by means of hand-latches b^5 , working through the upper wall of the chutes. Just forward of these valves b^4 are branch chutes c , which open from the under sides or floors of said chutes b^3 and join in a common 70 flaring mouthpiece or nozzle c' , located in position to deliver a blast onto the separating screens or riddles a^6 .

a^{14} is a pivoted section of the inclined rear end wall of the thresher-frame a . This pivoted section permits easy access to the separating-sieves a^6 .

The space immediately below the delivery ends of the air-chutes b^3 is formed into a two-pronged draft-chute g by a V-shaped divider g' , which, as shown, is located centrally on the pivoted rear wall-section a^{14} and provided with a top or check board g^2 of the same width as the interior of the separator-casing. The lower or receiving mouth of this divided chute 80 g is in position to receive and draw off the dust and chaff from the separating-screens 85 a^6 , as will later more fully appear.

The operation is substantially as follows: Rotation is imparted to the fans b and cylinder a^2 by means of a power-driven belt (not shown) applied to the pulley a^{12} . Motion is imparted to other parts of the threshing and separating mechanism through a driver, (not shown,) but which may be driven from the 90 pulley a^{13} on the cylinder-shaft a^3 . Motion being thus imparted, the ordinary threshing and separating actions will take place. The fans being thus rotated at a high speed will of course create a strong forced draft through the chutes b^3 , which being discharged from the rear ends of said chutes into the base of the stacker tube or trunk $a^8 a^9$ continues the forced draft through said stacker-trunk $a^8 a^9$.

Under this action, as is obvious, the straw discharged from the tables or racks a^4 into the base of the stacker-trunk will be forced through and discharged at the upper end of 5 said stacker-trunk. The forced draft through the chutes b^3 and stacker-trunk a^8 a^9 causes a suction-draft through the draft-chute g , as indicated by the arrow marked therein on Fig. 4. This forced suction serves, as already indicated, to draw off the dust from the separating-screens a^6 . On passing through this suction-chute g the dust will be taken up and discharged with the straw through the stacker-trunk. By means of the cut-off valves b^4 15 more or less of the forced draft may be cut off from its natural or most direct course through the tubes b^3 and be diverted through the branch chutes c . Thus the blast on the separating-screens a^6 may be varied, as may 20 be found necessary, to give the proper cleaning action on said screens.

It will be seen from the above that the forced blast of air which is drawn off from the main air-chute and passed over the separating-screens will, after it has taken up the dust and chaff from the same, be sucked in through the suction-chute g and be reunited with the main draft.

It must be evident that by my novel arrangement of the fans and the air-chutes delivering therefrom in the manner above set forth the construction of the machine is greatly simplified and the operation of the same correspondingly bettered.

35 It will be understood, of course, that various alterations of the details of construction might be made without departing from the spirit of my invention.

What I claim, and desire to secure by Letters Patent of the United States, is as follows:

1. In a threshing-machine, equipped with a

pneumatic stacker and coöperating fan, the combination therewith of the main air-chute discharging into the base of said stacker trunk or tube, a suction-tube having its receiving end positioned near the separating-screens and its discharge end opening into the blast from said main air-chute, whereby the blast of air which is drawn off from the main air-chute and passed over the separating-screens, will be again united with the main draft, substantially as described. 45

2. In a threshing-machine, equipped with a pneumatic stacker and a pair of coöperating fans, the combination therewith of the pair 55 of main air-chutes discharging into the base of the stacker trunk or chute, the pair of branch tubes leading one from each of said main air-chutes, to the separating-screens, and a divided suction-tube having its receiving end positioned near the separating-screens and its discharge end opening into the blast from said main air-chute, substantially as described. 6c

3. In a threshing-machine equipped with a 65 pneumatic stacker, the combination with the threshing-cylinder, of the pair of fans b , secured on the cylinder-shaft, the fan-cases b' inclosing said fans, the air-chutes b^3 leading from said fan-cases b' , the hand-operated 70 valves b^4 b^5 in said chutes b^3 , the branch chutes c terminating in nozzle c' , and the two-branched suction-passage g g' g^2 , on the inclined rear wall of the thresher-case, substantially as described. 75

In testimony whereof I affix my signature in presence of two witnesses.

GODFREY W. PAPKE.
